UNITED STATES PATENT OFFICE

SYLVAN M. BYCK, OF SAVANNAH, GEORGIA

LIGHT

Application filed April 6, 1929. Serial No. 353,104.

This invention relates to new and useful improvements in lighting devices primarily designed for submersion for aquatic use.

An object of the invention comprehends the provision of means whereby the light may be arranged upon and within the walls of pools and the like to illuminate the entire pool and to produce a pleasing effect wherever night bathing is desired.

10 Another object of the invention embodies a lens of heat resisting and high transmission characteristics.

More specifically stated the fixture is provided with means to facilitate drainage whereby seepage and condensation may be carried off to obviate short circuits and other difficulties which might impair the proper and normal functions of the fixture.

With the above and other objects in view, 20 the invention further consists of the following novel features and details of construction, to be hereinafter more fully described, illustrated in the accompanying drawings and pointed out in the appended claim.

25 In the drawings:—

Figure 1 is a side elevation of the present invention as arranged within a wall.

Figure 2 is a front elevation of the fixture per se.

30 Figure 3 is a longitudinal sectional view taken through the fixture.

Figure 4 is a horizontal sectional view taken on line 4—4 of Figure 3.

Referring to the drawings in detail where- 35 in like characters of reference denote corresponding parts, the reference character 10 indicates a lamp casing or housing of any desired shape and which is constructed to provide an enlarged side wall portion 11 ad- 40 jacent the periphery thereof, substantially as illustrated in Figures 1 and 3 of the drawings.

The housing or lamp casing, in its entire- 45 ty, is wholly disposed within a wall structure, as evidenced from the illustration of my invention in Figure 1 of the drawings and such structure may be in the nature of the side wall of a pool whether employed for bathing or aquatic plant and animal life.

50 The peripheral edge of the annular enlarged

portion 11 of the lamp casing or housing is preferably aligned with the adjacent surface of the wall structure. Said enlarged portion is provided with a recess 12 to accommodate a resiliently composed packing washer or seat 13 upon the shoulder portion as defined between the enlarged portion proper and the recess 12.

A lens, such as indicated at 14, of cylindrical convex formation, is threaded in such manner as to possess the characteristic factors of heat resistance and high penetrating transmission for purposes which will be hereinafter more fully set forth in detail. A companion gasket 15, constructed after the manner of the packing or gasket 13, is engageable with the outer surface of the lens 14 in oppositely disposed relation to the aforementioned gasket whereby the marginal edges of the lens will be yieldingly retained in position but yet provided with a leak proof means of securement. An annulus or locking ring 16, threaded upon the outer surface thereof, is adjustably mounted within the recess 12 and engageable with a metal collar or shim 17 interposed between the inner side and the adjacent outer surface of the companion packing washer 15.

A bead 18, of annular formation formed upon the outer surface of the lens 14 in spaced relation to the marginal edge of the lens proper, compensates or cooperates with the outermost or companion packing washer 15 in the compressing of the latter against the lens to render the connection therebetween leak proof. The rim 16 has notches 19 at intervals to facilitate projection or accommodation of the fins or studs carried by a spanner wrench or the like, not shown, whereby the ring may be threaded within the recess 12 to a desired depth and to exercise a certain pressure against the outermost of the gaskets 15 as against the lens 14 to insulate the interior of the lamp casing or housing from the contents of the pool.

However, it may so happen that condensation or seepage of the contents of the pool, within the lamp casing or housing, would impair proper illumination of the

water from the particular lamp and for this reason I have provided a drain or other pipe, such as indicated at 20, having connection at its uppermost end with the under side of the casing or housing 10 within the wall structure and having communication at its opposite end with a receptacle, preferably embedded within the soil adjoining the wall structure and preferably filled with 5 gravel and the like, not shown, to prevent undermining of the wall structure by fast flow. A receptacle 21, preferably located upon the inner side of the bottom wall of the casing or housing, accommodates the 10 socket end of an incandescent lamp bulb 22, preferably of the type having a neck or extension 23. The latter mentioned bulbs are of the conventional type used for high voltage.

15 A reflector 24, arranged within the housing or casing, is provided with a rearwardly projecting centrally disposed sleeve portion 25 telescopically associated with the neck portion 23 of the lamp bulb 22 to facilitate 20 projection of the latter therethrough for connection with the receptacle 21. The reflector is furthermore provided with facets 26, 27 and 28 respectively, so arranged about the lamp bulb 22 as to reflect and refract or 25 otherwise diffuse the light rays therefrom whereby the light subsequently reflected through the lens 14 will be of an illuminating nature but devoid of glaring or blinding effect.

30 Clamping members or ears 29, having feet or offset portions 30 upon the innermost ends thereof, are engageable with the peripheral edge of the reflector 24 in the manner shown in Figures 3 and 4 of the drawings. The said clamps or ears are 35 bifurcated to define slots 31 and arms 32 by means of which the shanks of fastening elements, generally designated as at 33, may be extended between the arms 32 and within the slots 31 for ultimate projection with- 40 in tapped openings within the adjacent wall of the lamp casing or housing. The adjacent sides of the heads of the fastening elements 33 frictionally engage the adjacent surfaces of the arms 32 to secure the clamps or ears in desired regulated positions whereby the reflector 24 after being shifted to properly focus the light may be 45 rigidly retained in such position in order that the contents of the pool may be effectively illuminated.

Enlarged portions or bosses, such as indicated at 34, and preferably located upon diametrically opposite sides of the housing 50 or lamp casing exteriorly thereof, are bored and tapped to accommodate the adjacent ends of conduits or other pipes, such as indicated at 35.

Said conduits are employed for conveying 55 and housing conducting wires to and from

the respective receptacle of the lamp casings.

The several parts of the invention may be 70 formulated or treated in such manner as to render same impervious to moisture and to resist rust and corrosion; especially is this true in the reflector, inasmuch as the latter is constructed of glass with coatings of silver plate and copper.

By reason of the fact that the peripheral 75 edge of the enlarged portion 11 of the housing is arranged flush and in alignment with the adjacent surface of the wall structure, the rays of the diffused light reflected from the lamp casing will illuminate the utmost 80 of the immediate area of the water in the pool.

The invention is susceptible of various 85 changes in its form, proportions and minor details of construction, and the right is 90 herein reserved to make such changes as properly fall within the scope of the appended claim.

Having thus described the invention, what 95 is claimed is:—

A subaqueous light comprising a housing, 100 a reflector for the housing movable rectilinearly thereof toward and away from the projection end thereof, arms of angular formation arranged at intervals upon the projecting periphery of the reflector having the remaining portions of their lengths slotted and lying flush against the adjacent surface of the housing, fastening elements carried by the housing and projecting through said slots to retain said reflector 105 against displacement from adjusted position, and an illuminating element having support upon the housing slidably connected with the reflector to facilitate the reflecting, diffusing and focusing of the rays of light therefrom.

In testimony whereof I affix my signature.
